UNITED STATES PATENT OFFICE.

ARTHUR GILBERT ARNOLL, OF GLENDALE, CALIFORNIA, ASSIGNOR TO NATIONAL CARBON COMPANY, INC., A CORPORATION OF NEW YORK.

DESIGN FOR A FLASHLIGHT-HEAD.

57,760.

Specification for Design.

Patented May 3, 1921.

Application filed November 24, 1920. Serial No. 426,297. Term of patent 14 years.

To all whom it may concern:

Be it known that I, ARTHUR GILBERT ARNOLL, a citizen of the United States, residing at Glendale, in the county of Los Angeles and State of California, have invented a new, original, and ornamental Design for a Flashlight-Head, of which the following is a specification, reference being

had to the accompanying drawing, forming part thereof, wherein the single figure illustrates in perspective a flashlight casing with the novel head applied thereto.

I claim:

The ornamental design for a flashlight head as shown.

ARTHUR GILBERT ARNOLL.
